The ornamental design for a multimedia anti-tampering device, as shown and described.

DESCRIPTION

FIG. 1 is a first perspective view of a multimedia anti-tampering device;

FIG. 2 is a second perspective view thereof;

FIG. 3 is a bottom plan view thereof;

FIG. 4 is a top plan view thereof;

FIG. 5 is a left side elevational view thereof;

FIG. 6 is a right side elevational view thereof;

FIG. 7 is a rear elevational view thereof; and,

FIG. 8 is a front elevational view thereof.

The ornamental design which is claimed is shown in solid lines in the drawings. The broken line showing is included for the purpose of illustrating portions of the multimedia anti-tampering device and forms no part of the claimed design.
